Ms. 1737

George Green, of Wappingers Falls, N.Y.
assor. to

Deborah Powers, Albert C. Powers, and

Nathaniel B. Powers, of Lanesburgh, N.Y.

Letters Patent No. 1737. dated March 17. 1863.

The schedule referred to in these Letters Patent and making part of the same.

To all whom it may concern:

Be it known that I, George Green, of Wappingers Falls, in the County of Dutchess, and State of New York, have invented and produced a new and original design for Floor Cloth cloths or other fabrics; and I do hereby declare that the following is a full and exact description of the same, viz. The pattern consists of a large octagon of light color, having placed upon it an ornament in white or lighter color, and is surrounded by a line of dark brown color, which is again surrounded by a line of the same color as the ground of the octagon, the whole being placed upon a dark brown ground; this ground is surrounded by black or marrow lines, and upon the intersection of said lines is placed an octagon also of black or marrone, which has a line of the brown color placed near its margin, and a cross or rosette of the same in its centre.

And what is claimed as my invention, and desired to be secured by letters patent is the aforesaid design as shown upon the drawings accompanying this specification and which are hereby declared to be a part of the same.
